UNITED STATES PATENT OFFICE.

WILLIAM B. PLACE, OF WEST HAVEN, CONNECTICUT, ASSIGNOR TO THE AMERICAN BUCKLE AND CARTRIDGE COMPANY, OF SAME PLACE.

MACHINE FOR WINDING WADS FOR PAPER CARTRIDGES.

SPECIFICATION forming part of Letters Patent No. 393,028, dated November 20, 1888.

Application filed August 1, 1887. Serial No. 245,844. (No model.)

To all whom it may concern:

Be it known that I, WILLIAM B. PLACE, residing at West Haven, in the county of New Haven and State of Connecticut, have invented 5 certain new and useful Improvements in Machines for Winding Wads for Paper Cartridges; and I do declare the following to be a full, clear, and exact description of the same, reference being had to the accompanying drawings, which form a part of this specification.

My invention relates to an improved machine for winding wads for paper cartridges, the object being to produce a simple, compact, and durable machine having a large capacity for work and adapted to be easily operated and repaired.

With these ends in view my invention consists in a machine having certain details of construction and combinations of parts, as will 20 be hereinafter described, and pointed out in the claims.

In the accompanying drawings, Figure 1 is a view, partly in side elevation and partly in vertical longitudinal section, of one form which 25 a machine embodying my invention may assume. Fig. 2 is a view of the machine in front elevation with the tube-carrying dial, the box, plunger, wad-winding shaft, and their attachments removed, the arm H' being broken away 30 behind the double cam to show the pulleys at the back of the machine. Fig. 3 is a view of the machine, partly in plan and partly in section, on the line a b of the preceding figure, being broken away just back of the forward upright. Fig. 4 35 is a detached view in inside elevation of the box with the die-holder in place therein. Fig. 5 is a similar view in side elevation of the box and die-holder. Fig. 6 is a reverse plan view of the grooved bearing, box, die-holder, die, plunger, wad-winding spindle, and oscillating knife, 40 the forward upright being shown in section and the rotary collar with tripping-finger by broken lines. Fig. 7 is a detached view in side elevation of the plunger. Fig. 8 is a similar view of the spring wad-remover. Fig. 9 45 is a reverse plan view of the lower end of the plunger. Fig. 10 is a similar view of the lower end of the wad-remover. Fig. 11 is a detached view in side elevation of the die-holder. Fig. 12 is a reverse plan view thereof. Fig.

13 is a detached view in side elevation of the die. Fig. 14 is a reverse plan view thereof. Fig. 15 is a detached view in side elevation of the wad-winding shaft. Fig. 16 is a reverse plan view of the lower end thereof. Fig. 17 55 is a detached view in side elevation of the wad-winding spindle, and Fig. 18 is a reverse plan view thereof.

The parts shown in Figs. 4 to 18, inclusive, are shown one-third larger than in the other 60 views.

The bed A of the machine is provided upon its upper face with a forward transverse upright, B, and a similar rear upright, C, as shown. A driving-shaft, D, having bearing 65 in the upper ends of the said uprights, carries a double cam composed of the parts E and F at its forward end, a hand-wheel, G, for manually turning the shaft, a beveled gear, H, a loose pulley, I, through which the shaft is 70 driven, and a grooved coned sleeve, J, engaged by the fork K of bell-crank lever, L, connected by a rod, M, with a foot-lever, (not shown,) the said sleeve operating through an arm, O, to couple the said pulley with the shaft, 75 from which the pulley is uncoupled by a spring, P, withdrawing the sleeve from the said arm. The part E of the said double cam is provided in its outer face with a cam-slot, Q, receiving a pin, R, projecting inwardly from a head, S, 80 located at the upper end of a plunger, T, reciprocating in a vertical chamber formed by a semicircular groove, U, (see Fig. 2,) formed in the face V of a bearing, W, extending forward from the outer face of the forward up- 85 right, B, and by a similar groove, X, (see Fig. 4,) formed in the inner face of a box, Y, secured to such bearing and provided with upright shoulders Z, Z', entering corresponding recesses, A' A', formed in the said face of the 90 bearing. The said plunger is provided upon its inner face with a longitudinal slot, B', receiving a spline, C', located in a vertical slot, D', formed in the face of the bearing W aforesaid and held in place therein by a screw, E', 95 the said spline guiding the plunger and preventing it from turning.

A vertical rotary wad-winding shaft, F', extends into the longitudinal opening G' of the plunger, which reciprocates over it, such shaft 100

being suspended from an arm, H', secured to and extending forward from the forward upright, B, and prevented from endwise movement by a collar, I', located below the arm 5 and a pulley, J', located above the same. A belt, K', running over such pulley, also runs over a pulley, L', mounted on a vertical shaft, M', located in the upper end of a heavy standard, N', secured to the rear end of the bed of 10 the machine. A friction-disk, O', couples the pulley L' with a pulley, P', mounted on the same shaft therewith and carrying a belt, Q', running over two inclined pulleys, R' R', mounted in an extension, S', of the standard; and also 15 over a driving pulley. (Not shown, but adapted to impart a high rate of speed to the wad-winding shaft.) An idle-pulley, T', mounted on a pivotal arm, U', engages with the belt K' and preserves the same in proper tension. 20 The friction-coupling between the pulleys L' and P' will be adjusted so that when the wad-winding shaft is stopped, as will be hereinafter explained, the pulley L' will slip and leave the belt K' and pulley J' practically idle, whereby 25 the belt will be prevented from slipping upon the pulley J' and burning out.

A removable wad-winding spindle, V', having its lower end split, as at W', to receive the end of the stock-strip X', (see Fig. 1,) is 30 secured in a bore, Y', formed in the lower end of the wad-winding shaft.

A cylindrical die, Z', having a circular opening, A', corresponding to the exterior diameter of the wads to be wound, is provided 35 at its lower end with four vertical slots, B' B' B' B', and as many straight cutting-edges, C', and retreating clearance-spaces D', the slots and spaces admitting the stock-strip to the said spindle, with which the die is concentric. 40 By providing the die with four slots, as described, four cutting-edges are secured for it, whereby it may be four times changed in position, as the edges are dulled, before removing it for sharpening them.

45 A cylindrical shiftable die-holder, E', having a central opening, F', receives therein the die aforesaid, and is provided at its lower end with four vertical equidistant curved clearance-slots, G' G' G' G', arranged in alignment with 50 the slots of the die and shaped to give clearance to the knife H', working against the cutting-edges of the die, which is secured in the holder by a screw, I', entering the lower end of the box Y and then passing through the holder at 55 a point above the slots. The lower end of the said die-holder depends below the bearing W and box Y, while its upper end extends into a chamber formed by offsetting the lower end of the groove U, as at J', (see Fig. 2,) and 60 similarly offsetting the groove X, as at K', as shown by Figs. 2 and 4 of the drawings. It is secured in place by removable pins L' L' and is adapted by its provision with four slots to be shifted either with or independent of the 65 die and used in four positions. The plunger extends into and plays in the upper end of the said holder, the slots of which assist in guid-

ing and giving right direction to the stock-strip.

A cylindrical spring wad-remover, M', having a central longitudinal opening, N', adapting it to receive the wad-winding spindle V', over which it reciprocates, is provided at its upper end with a threaded taper, O', entering a similar tapering and threaded counterbore, P', formed in the lower end of the plunger, its lower end being adapted to play in the die aforesaid. The said remover is provided with four equidistant vertical slots, O' O' O' O', admitting the stock-strip X' to the spindle V', 70 and extending from its lower end up into the taper O', whereby the remover may be contracted by screwing it into the plunger or expanded by unscrewing it therefrom, adapting it to be compensated for wear and to be 75 conformed within limits to the sizes of the wads. The arrangement of the slots in the remover also adapts it to be shifted and used in four positions, the slots of the remover, die, and die-holder being always set in alignment with the 80 slot W' in the lower end of the wad-winding spindle. 85

Normally the wad-winding shaft F' is rotated by its driving-connections, which have already been described. It is stopped, however, by the friction developed between the die and the wad wound upon the spindle, and subsequently positively coupled with the plunger by a two-part clutch composed of a stationary head or collar, Q', secured to the head S, and having 90 projections R' upon its lower face and a movable rotary head or collar, T', having projections U' upon its upper face and mounted upon the rod to which it is connected by a pin, V', playing in a longitudinal slot, W', formed in 95 the rod upon which the collar moves, the part T' being supported and in part operated by a spiral spring, X', located in a chamber, Y', formed in the upper end of the plunger and interposed between the movable collar and the 100 bottom of such chamber.

The bevel-gear H aforesaid meshes into a similar gear, Z', supported upon an arm, A', projecting from the outer face of the upright C and secured to the upper end of an upright 115 shaft, D', extending below the bed of the machine and provided with a bevel-gear, E', meshing into a similar gear, F', mounted on a horizontal shaft, G', supported in bearings H', depending from the bed of the machine 120 and provided with a bevel-gear, I', meshing into a similar gear, J', located at the lower end of an upright shaft, K', extending beside the bearing W, as shown. A horizontal feed-cam, L', located upon the upper end of the 125 said shaft K' and having its acting-edge serrated, engages with the end of the stock-strip X', which travels through a guideway, M', secured to the bed of the machine and receiving the strip from a slot, N', formed in the flange 130 O' of a horizontal disk, P', carrying the stock-coil and supported upon an arm, Q', as shown.

A knife, H', for severing the wad from the strip, is attached to a horizontal cutter-head,

S³, secured to the lower end of a short oscillating shaft, T³, mounted in the bearing W, the said cutter-head being provided with a finger, U³, which is engaged by a finger, V³, formed upon a collar, W³, secured to the power-driven shaft K³ before mentioned, whereby the knife will be advanced once for every revolution of the shaft K³, and hence of the feed-cam. A spring, X³, eccentrically connected 10 with the upper end of the shaft T³, operates to oscillate the shaft T³, and so automatically retire the knife after it has done its work.

A bent arm, Y³, secured to the outer face of the head S, is provided at its outer end with a sleeve, Z³, receiving a rod, A⁴, free to play in such sleeve and provided at its lower end with a wedge, B⁴, between which and the said sleeve is interposed a spiral spring, C⁴, permitting the wedge to yield. The wedge is provided for 20 expanding and uniforming the upper ends of the paper tubes D⁴, which are manually supplied to a horizontal dial, E⁴, mounted upon the bed of the machine, so that its edge will be rotated under the winding and ejecting mechanism explained.

The dial is advanced step by step to successively bring its tubes under the plunger by the engagement with a ratchet, F⁴, formed in its lower edge, of a spring-actuated pawl, G⁴, pivoted to a slide, H⁴, inclosed in a box or bearing, I⁴, extending transversely across the bed of the machine and parallel with and at the foot of the forward upright, B.

A lever, J⁴, positively operating the slide 35 for advancing the dial, is connected at its lower end with such slide fulcrumed midway of its length to the outer face of the forward upright upon a stud, K⁴, and provided at its upper end with a roll, L⁴, engaging with the cam-periphery of the part F of the double cam. A spring, M⁴, having one end attached to the rear end of the slide and the other end to an arm, N⁴, operates to retract the slide to bring the pawl into position to engage with another 45 tooth of the ratchet F⁴ before mentioned.

Having set forth in detail the construction of my improved machine, I will now proceed to describe the mode of its operation.

Let it be assumed, for convenience, that a 50 wad has just been wound and introduced into a tube and that the several parts of the machine are in position for a repetition of the operation. In the first place, then, the feed-cam L³ engages its serrated edge with the end of the stock-strip X³ and feeds the strip forward, its free end passing through the aligned slots of the die-holder, the die, the wad-remover, and the wad-winding spindle. As soon as the strip has been advanced and entered, as described, the part E of the double cam lifts the 55 plunger T, thereby withdrawing the wad-remover out of the die and clearing the same for the wad and lifting the stationary collar Q² of the two-part clutch, the parts whereof 60 are at this time engaged. The spiral spring X², however, lifts the movable part of the clutch as rapidly as the plunger lifts the sta-

tionary part thereof, so that they remain coupled until just before the plunger completes its upstroke, when the pin V² engages with the upper wall of the slot W² and stops the movable collar, from which the stationary collar is now disengaged by the completion of the upstroke of the plunger. The clutch being broken, the wad-winding shaft is rotated with great 75 rapidity. The feed-cam in the timing of the parts being now out of the way, the spindle draws in the stock-strip freely and rapidly winds the wad, which when completed engages with the walls of the die with the development 80 of so much friction that the shaft is stopped. The finger V³ now engages with the finger U³, located upon the cutter-head, and swings the knife H² through the adjacent curved clearance-slot of the die-holder and cuts the strip 85 on the adjacent cutting-edge of the die. This done, the said fingers are disengaged, when the spring X³ at once swings the head and knife out of the way into retirement. The plunger is now started on its downward stroke by the 90 double cam, and almost immediately engages the collar Q² with the collar T² and couples the plunger and wad-winding shaft, which are already frictionally coupled by the wad which is still in the die. After this the two collars 95 remain in engagement while the plunger completes its downstroke and until just before it reaches the limit of its next succeeding upstroke. As the plunger descends, the wad-remover enters the die and gradually forces the 100 wad therefrom and into the tube then under the die, the wad being, in fact, stripped from off the spindle which has no endwise movement. As soon as the wad has been removed from the spindle and the same relieved from 105 friction, the shaft is sufficiently rotated by its driving-connections to engage the projections of the collars if they were not properly engaged when the coupling took place, such projections being arranged so that when engaged 110 the slot in the spindle is in alignment with the end of the stock-strip. The strip is now fed forward as before, the plunger elevated, the wad-winding shaft uncoupled for rotation, the wad wound and cut off, the shaft stopped by 115 friction, the plunger depressed, the clutch re-coupled, the wad removed and introduced into a tube brought under it by the advancement of the dial, and so on. It will thus be seen that the wad is wound during the short period 120 wherein the winding-shaft is uncoupled and occurring at the upstroke of the plunger.

The plunger being actuated directly from the shaft and positively in both directions under my invention, the machine may be timed 125 very closely in this as well as in other respects.

It is apparent that some change may be made in the machine as herein shown, and I would therefore have it understood that I do not limit 130 myself to the exact construction shown and described, but hold myself at liberty to make such changes and alterations as fairly fall within the spirit and scope of my invention.

Having fully described my invention, what I claim as new, and desire to secure by Letters Patent, is—

1. In a machine for winding wads, the combination, with a driving-shaft, of a cam secured thereto, a plunger connected directly with and positively actuated by such cam, and an intermittently-rotated wad-winding spindle, substantially as set forth. 10
2. In a machine for winding wads, the combination, with a plunger and a wad-winding spindle, of a die having more than one cutting-edge and adapted to be shifted in position, substantially as set forth. 10
3. In a machine for winding wads, the combination, with a plunger and a wad-winding spindle, of a slotted die and a shiftable die-holder having clearance-slots arranged to align with the slots of the die, substantially as set forth. 20
4. In a machine for winding wads, the combination, with a plunger and a wad-winding spindle, of a fixed die-holder and a removable die, substantially as set forth. 20
5. In a machine for winding wads, the combination, with a plunger and a wad-winding spindle, of a die, an oscillating knife, and a rotary finger for operating the same, substantially as set forth. 25
6. In a machine for winding wads, the combination, with wad-winding mechanism, of a cutter secured to an oscillating cutter-head provided with a finger, a rotary feed-cam, and a finger rotating therewith and engaging with the finger of the cutter-head, substantially as set forth. 30
7. In a machine for winding wads, the combination, with a plunger and a wad-winding spindle, of a slotted die, a die-holder provided with curved clearance-slots, and an oscillating knife, substantially as set forth. 40
8. In a machine for winding wads, the combination, with a plunger and a wad-winding spindle, of a removable wad-remover, substantially as set forth. 45
9. In a machine for winding wads, the combination, with a plunger and a wad-winding spindle, of a removable shiftable wad-remover, substantially as set forth. 50
10. In a machine for winding wads, the combination, with a plunger and a wad-winding spindle, of an expansible and contractile wad-remover, substantially as set forth. 55
11. In a machine for winding wads, the combination, with a plunger and a wad-winding spindle, of a wad-remover having a threaded taper at its upper end and slotted from its lower end up into such taper, which screws into the lower end of the plunger, substantially as set forth. 60
12. In a machine for winding wads, the combination, with a plunger, a slotted wad-winding spindle, a slotted wad-remover, a slotted die, and a slotted die-holder, the slots of the slotted parts being arranged in alignment, substantially as set forth. 65
13. In a machine for winding wads, the combination, with a plunger, of a wad-winding spindle and a rotary coupling for such plunger and spindle located within the former, substantially as set forth. 70
14. In a machine for winding wads, the combination, with a plunger, of a wad-winding spindle, a coupling for such plunger and spindle located within the plunger, and a spring located within the plunger and maintaining the coupling, substantially as set forth. 75
15. In a machine for winding wads, the combination, with a vertical plunger and a wad-winding spindle, of a two-part clutch having one part fixed to the plunger and the other part movably connected with the spindle, and a spring for sustaining the two parts of the clutch in engagement during a portion of the time that the plunger is on its upstroke, substantially as set forth. 80
16. In a machine for winding wads, the combination, with a vertical plunger and a wad-winding shaft provided with an elongated slot, of a two-part clutch, of which one part is fixed to the plunger and the other movably mounted upon the shaft, a pin located in the slot in the shaft and limiting the movement of the movable clutch part mounted thereupon, and a spring located in a chamber in the plunger and sustaining the two parts of the clutch in engagement during a portion of the time that the plunger is on its upstroke, substantially as set forth. 85
17. In a machine for winding wads, the combination, with a bed, of a shaft parallel therewith, a cam located at one end of such shaft, a plunger actuated directly from such cam, a wad-winding spindle, a strip-cutter, and a strip-feed, and gearing from the shaft to the feed and located in part under the bed of the machine, substantially as set forth. 90
18. In a machine for winding wads, the combination, with a plunger and a wad-winding spindle, of a wedge connected with the plunger for expanding the upper ends of the tube, substantially as set forth. 95
19. In a machine for winding wads, the combination, with a plunger and a wad-winding spindle, of a spring or yielding wedge for expanding the upper ends of the tubes connected with the plunger, substantially as set forth. 100
20. In a machine for winding wads, the combination, with a plunger and a wad-winding spindle, of an arm connected with the plunger, an upright rod mounted to slide in the outer end of such arm and provided at its lower end with a wedge for expanding the tubes, and a spring interposed between such arm and wedge, substantially as set forth. 105
21. In a machine for winding wads, the combination, with a plunger, of a wad-winding shaft extending into it, a wad-winding spindle located at the lower end of such shaft, a removable wad-remover located at the lower end of the plunger, a die-holder, and a removable die, substantially as set forth. 110
22. In a machine for winding wads, the combination, with an upright, of wad-winding

mechanism secured thereto, a dial, a pawl for advancing the same step by step, a slide located at the foot of the upright under the winding mechanism transverse to the bed of the machine and having the pawl pivoted to it, and a lever pivoted to the face of the upright and connected to the slide, which it actuates in one direction, substantially as set forth.

23. In a machine for winding wads, the combination, with a driving-shaft, of a double cam located at one end thereof, a plunger connected directly with one part of such cam, a wad-winding shaft over which the plunger recipro-

cates, a dial having a circular ratchet, a pawl engaging with such ratchet, and a lever actuated by the other part of said cam and connected with and actuating such pawl, substantially as set forth. 15

In testimony whereof I have signed this specification in the presence of two subscribing witnesses.
